CLAIM

The ornamental design for convertible children's furniture, as shown and described.

DESCRIPTION

FIG. 1 is a front-top-right perspective view of a convertible children's furniture in a closed configuration, showing my new design;

FIG. 2 is a front-top-left perspective view thereof;

FIG. 3 is a front-bottom-right perspective view thereof;

FIG. 4 is a front-bottom-left perspective view thereof;

FIG. 5 is a rear-bottom-left perspective view thereof;

FIG. 6 is a front elevation view of the present design, showing the planes upon which a cross sectional views are taken shown in FIGS. 12 and 13.

FIG. 7 is a front elevational view thereof;

FIG. 8 is a rear elevational view thereof;

FIG. 8 is a top plan view thereof;

FIG. 9 is a bottom plan view thereof;

FIG. 10 is a left elevational view thereof;

FIG. 11 is a right elevational view thereof;

FIG. 12 is a transversal cross-sectional view taken along line 12-12 in FIG. 6.

FIG. 13 is a transversal cross-sectional view taken along line 13-13 in FIG. 6.

FIG. 14 is a rear-top-right perspective view of the present design in an alternate configuration; and,

FIG. 15 is a rear-top-left perspective view of the present design in an alternate configuration.

The broken line showing fastener openings in FIGS. 1-5, 10-11, and 14-15 is included for the purpose of illustrating environmental structure and forms no part of the claimed design.

1 Claim, 15 Drawing Sheets
